UNITED STATES PATENT OFFICE.

NILS OLOF CRONWALL, OF HAMBURG, GERMANY.

PISTON-ROD OR OTHER SIMILAR PACKING.

SPECIFICATION forming part of Letters Patent No. 695,195, dated March 11, 1902.

Application filed July 18, 1901. Serial No. 68,861. (No model.)

To all whom it may concern:

Be it known that I, NILS OLOF CRONWALL, engineer, of 29 Rutschbahn, Hamburg, in the Empire of Germany, have invented new and useful Improvements Relating to Piston-Rod or other Similar Packings, (for which patent applications have been made in Germany, filed June 14, 1901, and in Great Britain, filed June 20, 1901,) of which the following is a specification.

This invention relates to piston-rod and other similar packings, and has for its object to provide improved means whereby tight and durable joints may be made for piston-
15 rods in the cylinder-cover or for other parts of machinery.

The ordinary manner of forming a tight joint for piston-rods by means of hemp, asbestos, or metallic alloys inserted in the
20 stuffing-box has the objection of causing great wear of the piston-rod by friction, and consequently the loss in power arising therefrom. All three modes of packing affect the continuous working of the engine in so far
25 that it is necessary to tighten such packings from time to time, whereby excessive tightening of the stuffing-boxes often occurs. This excessive tightening is difficult and often impossible to properly control and produces
30 undue heating of the piston-rod. Furthermore, with the methods of packing hitherto employed, especially when applied to marine engines, deviation of the piston-rod is not provided for, so that the one-sided stress
35 thus produced on a very small frictional surface causes undue heating of the piston-rod.

All the above-mentioned objections are obviated according to this invention by the introduction into the stuffing-box of metal
40 bushes pressed radially against the piston-rod by means of springs in such a manner that tightening or readjustment of the same will be unnecessary. On the contrary, the construction and arrangement is such as to insure a more and more tight joint with continuous service.

In order that my invention may be clearly understood and readily carried into effect, I will now proceed to describe the same more fully with reference to the accompanying drawings, in which—

Figure 1 is a vertical section of a cylinder

stuffing-box provided with my improved packing device. Fig. 2 is a horizontal section through the same, taken on the line A B of 55 Fig. 1. Fig. 3 is a plan, and Fig. 4 is an elevation, of my improved packing-bush.

The piston-rod *a* is guided in a bottom ring *b*, disposed in the cylinder-cover *c*. Below the ring *b* the cylinder-cover is formed 60 with a stuffing-box *d*, serving to receive the packing device.

The packing consists of a sleeve *e*, longitudinally slotted in several places and adapted to be pressed against the piston-rod by means 65 of springs *f*. On the inner face of the said packing-sleeve *e* are formed circular oil-grooves *e'*. In order to prevent steam passing through the slits *g*, said sleeve *e* is preferably provided with end pieces *h*, which 70 are prevented from peripheral displacement by means of pins *i*, secured to the several sections of the packing-sleeve *e*. The packing-sleeve thus constructed is seated on a washer or ring *k*, ground upon the bottom 75 guide-ring *b* of the stuffing-box, and is pressed against the ring *k* by springs *l*, held between two rings *m* and *n* in suitably-milled recesses formed in the adjacent faces of the latter. The back of the ring *m* rests against a ring *o*, mov- 80 ably disposed upon the piston-rod *a*, which ring *o* is secured to the stuffing-box *d* of the cylinder-cover by means of bolts *q*, fixed in the flange *p*. The ring *o* and flange *p* are advan- 85 tageously supplied with an asbestos packing to form a tight joint. The steam-tightness of this improved packing is insured by the fact that the sleeve-sections *e*, pressed against the piston-rod by the springs *f*, prevent steam es- 90 caping at that part. The slits *g*, formed by cutting the sleeve *e*, are closed by the parts of the sectional ring *h*, and any steam which may pass through the bottom guide-ring *b* and washer *c* and through the latter and the pack- 95 ing-sleeve *e* is prevented from escaping by reason of the asbestos ring provided between the ring *o* and flange *p*. The longer the en- 100 gine works the better the packing-sleeve *e* becomes ground upon the piston-rod, so that there is no fear of the joint becoming defective through long use. The circular oil-grooves *e'* become gradually filled with oil, and thus not only serve in supplying lubrication, but also in providing a tight joint. As by lengthy.

use the joint becomes all the more perfect, it is unnecessary to readjust or tighten the stuffing-box, besides the arrangement of stuffing-box is such as not to admit of further tightening. The springs *f* press the sleeve-sections *e* uniformly and in accordance with the wear against the piston-rod *a*, so that no attention need be given to the stuffing-box. By reason of the yielding or elastic disposition of the packing-sleeve it is capable of following any deviation of the piston-rod, and thus preventing the latter becoming overheated, owing to one-sided pressure.

What I do claim as my invention, and desire to secure by Letters Patent, is—

1. In a device of the character described, a sleeve having a series of longitudinal slots formed on the periphery thereof, a ring mounted upon one end of said sleeve and secured thereto by pins, springs engaging in said slots and guided by the walls thereof, a ring engaging the other end of said sleeve, spiral springs one end of which engages said ring, a ring en-

gaging the other ends of said spiral springs, and a ring movably mounted on the piston-rod which engages said last-named ring, substantially as described. 25

2. In a device of the character described, a sleeve composed of sections, the periphery of said sleeve being longitudinally slotted 30 and having springs mounted therein, a ring secured by means of pins to one end of said sleeve, a ring recessed on one face engaging the other end of said sleeve, spiral springs secured in said recesses, a ring recessed on one face which engages the other end of said spiral springs, and a ring movably mounted on the piston-rod and engaging said last-named ring, substantially as described. 35

In testimony whereof I affix my signature 40 in presence of two witnesses.

NILS OLOF CRONWALL.
